SHEET MATERIAL FEEDING MECHANISM

Moses E. Brooks, Pittsburgh, Pa., assignor to
 Aluminum Company of America, Pittsburgh,
 Pa., a corporation of Pennsylvania

Application July 29, 1936, Serial No. 93,215

4 Claims. (Cl. 271—2.5)

This invention relates to automatic sheet material feeding mechanisms for metal working machines such as shearing machines, and more particularly to mechanism for feeding sheet material into position for shearing.

Shearing machines having a reciprocating gate knife and a clamp which feeds successive lengths of sheet material into proper position to be sheared by the knife are well-known in the art. However, considerable difficulty is experienced with such machines when it is desired to shear uniform lengths of sheet material, since the running clearances between the parts which actuate the feeding clamp frequently accumulate in one direction, causing over-travel or under-travel of the said clamp and a consequent variation in the length of the piece fed to the shearing blade. When a high degree of accuracy and uniformity in the dimensions of all the pieces cut is desired, even comparatively small variations in length, resulting from under-travel or over-travel of the clamp, may cause much of the material cut to be unfit for the purpose desired. By means of the clamp-actuating mechanism of the type disclosed hereinafter, the possibility of over-travel or under-travel of the feed clamp is practically eliminated, and a high degree of uniformity in the length of the sheets cut can be obtained. With shearing machines constructed in accordance with my invention, it is possible to produce sheets having a length tolerance as low as plus or minus 5/1000 (0.005) of an inch.

One object of the invention is to provide an improved sheet material feeding mechanism for machines which will prevent variations in the length of sheets due to the accumulation of running clearances in the mechanism for actuating the feed clamp.

A further object of the invention is to provide a feeding mechanism having a feed clamp adapted to reciprocate between a fixed stop and an adjustable stop, the clamp being operatively connected with an improved mechanism for imparting reciprocal movement to it.

A further object of the invention is to provide an improved machine for handling sheet material, the machine having a feed clamp adapted to reciprocate between a fixed stop and an adjustable stop, the feed clamp being provided with mechanism for reciprocating it, and said mechanism including resilient means for absorbing over-travel.

A further object of the invention is to provide an improved apparatus for imparting a clamp-

ing action to the feed clamp of a machine such as a shearing machine.

Other objects of the invention will appear from the following description and claims and from the accompanying drawings, which are directed to the association of the mechanism of this invention with a shearing machine and in which:

Fig. 1 is a front elevation of the shearing machine;

Fig. 2 is a top plan of the machine, partly broken away to show the hold-downs, with the feed clamp at the end of its feeding movement;

Fig. 3 is a horizontal sectional view of the machine taken on the line III—III of Fig. 1, showing the lower section of the clamp at the end of the feeding movement;

Fig. 4 is a side elevation of the machine;

Fig. 5 is a fragmentary plan view to an enlarged scale of a portion of the mechanism shown in Fig. 3, showing the end of the lower section 20 of the feed clamp and the resilient means for absorbing over-travel in the clamp-actuating mechanism;

Fig. 6 is a detail side elevation of the end of the lower section of the feed clamp of Fig. 5 25 and of a portion of the clamp-actuating mechanism, including the resilient means for absorbing over-travel;

Fig. 7 is a detail sectional view taken on the line VII—VII of Fig. 9;

Fig. 8 is a fragmentary view to an enlarged scale of a portion of the mechanism shown in Fig. 4, showing the feed clamp at the end of its feeding movement, the fixed stop and the adjustable stop, and the mechanism which controls the operation of the pressure valve of the pressure cylinder which imparts a clamping action to the feed clamp;

Fig. 9 is a vertical sectional view taken on the line IX—IX of Fig. 8;

Fig. 10 is a vertical section through the knife-supporting cross-head, the feed clamp and the feed table on the line X—X of Fig. 2, showing the feed clamp at the end of its feeding movement, the pneumatic hold-downs pressing the sheet to the feed table, and the shearing knife descending to cut the sheet;

Fig. 11 is a view similar to Fig. 10, but showing the relative positions of the knife, the hold-downs and the clamp at the start of the feeding movement of the clamp.

Referring to Fig. 1, upright side members or housings, 1, 1, resting on the base 2 and connected at the top by a cross bar 3, together with feed table 4 extending between housings 1, 1, 55

form the main frame of the shearing machine. Crank shaft 5 is journaled through housings 1, 1, projecting beyond them at both sides, and supports reciprocable crosshead 6, which carries 5 knife 7 (Fig. 10), by means of sleeves 8 mounted on eccentrics on the crank shaft. Feed clamp 9, for feeding successive lengths of sheet material into shearing position, consists of upper and lower members 9a and 9b which extend across 10 said table 4 and are adapted for longitudinal reciprocation. Upper member 9a is also adapted for vertical reciprocation, as will be more fully described hereinafter, and is provided with a rubber gripping surface 10 (Fig. 10), which permits 15 more even clamping of the sheet material. The forward end of feed table 4 terminates in a seat for a fixed blade 11 which cooperates with knife 7 attached to cross-head 6 to shear the successive lengths of sheet material fed to the 20 blades by feed clamp 9. T-slot 12 at the other end of the feed table affords means for attaching an extension to the feed table, if desirable, which may include squaring guides. Member 9a of the feed clamp is provided with spaced 25 extensions 13 which, when the feed clamp is at the end of the feeding movement, project between pneumatic hold-downs 14 located between cross-head 6 and clamp 9 and carried by cross-beam 15 which is fastened to side members 1, 1. Member 9b is provided with spaced extensions 16 30 which coincide with extensions 13 and which, when the feed clamp is at the end of the feeding movement, project between pads 17 located beneath hold-downs 14. The projections 13 and 35 16 permit effective clamping of sheet material adjacent to the shearing blades, and thus reduce the amount of scrap.

Member 9a of the feed clamp is in the form 40 of a hollow beam and is U-shaped at each end to accommodate pressure cylinders 18, 18, as shown in Figs. 7 and 9, which cylinders each have a flanged base 19 resting on member 9b and bolted thereto by bolts 20, 20 passing through holes 21, 21 in said member. The bolt 20 likewise 45 clamps flanged bar 22 to the under-side of clamp member 9b, said bar having sliding bearing in T-slot 23 of table 4 and cooperating therewith to guide clamp 9 during longitudinal reciprocation on table 4. Pressure cylinder 18 is 50 equipped with valve 24 carried by a plate 25 which closes the U-shaped end of member 9a, which valve is connected to a pressure source and controls the admission of pressure to cylinder 18, thus controlling the vertical reciprocation 55 of piston rod 26 attached to the piston (not shown) of cylinder 18. Mounted on piston rod 26 by means of nuts 27 and 28 is strap 29, said strap having downwardly extending flanges 30, 30 suitably attached to clamp member 9a, where- 60 by vertical reciprocation of rod 26 results in a corresponding reciprocation of member 9a and a consequent opening and closing of clamp 9. The action of valve 24 in admitting pressure to the pressure cylinder is controlled by disc 31 65 (Figs. 8 and 9) mounted on crank-shaft 5 and having a cam surface 32, said disc bearing on roller 33 which is rotatable on pin 34 journaled in studs 35, 35 of piston 36. Piston 36 is integrally connected to rod 37 and is adapted to 70 reciprocate vertically in sleeve 38 attached to housing 1. Downward movement is imparted to said piston and rod by the action of cam surface 32 on roller 33 during the rotation of disc 31, and upward movement is produced by coil 75 spring 39 resting on seat 40 in sleeve 38 when

the pressure of cam surface 32 is released. Rod 37 extends through sleeve 38 and is pivotally connected to coupling 41 which is keyed to shaft 42 between bearings 43 and 44 fastened to side member 1, said shaft 42 extending parallel with 5 feed table 4 and being slidably mounted through bearings 45 and 46 integrally attached to plate 25. Located between bearings 45 and 46, and splined to shaft 42 for rotation with it, is sleeve 47 having a lug 48 slidably keyed in a groove 10 in said shaft and having an integral arm 49 pivotally connected to plunger 50 of valve 24. Reciprocation of rod 37 turns shaft 42, which in turn causes plunger 50 to reciprocate, and thus alternately admits and excludes pressure to or 15 from cylinder 18 in a known manner, thus reciprocating piston rod 26 and clamp member 9a, thereby opening and closing the clamp.

Lateral reciprocation of clamp 9 is produced by rocker arm 51 (Fig. 4) pivotally mounted on 20 housing 1 for oscillation about point 52, the oscillatory motion being imparted to said arm by means of pitman 53 which is pivotally connected to the extension 54 of said arm, and eccentric 25 55 mounted on crank shaft 5 and carrying said pitman. Connecting rod 56 is adjustably attached to rocker arm 51 by coupling 57 which extends through a slot in said rocker arm and is clamped in the desired position by nut 58. By 30 appropriately positioning connecting rod 56 in the slot of the rocker arm, the length of throw of said connecting rod may be regulated as desired. The distance said rod moves can thus be predetermined with the aid of the graduations on the rocker arm (see Fig. 4). Connecting rod 56 is pivoted to lever 59, which is pivotally mounted at one end to the housing. The other end of lever 59 carries clevis 60 which forms bearings for studs 61 and 62 of sleeve 63, which slidably 40 encircles a portion of rod 64, said rod having boss 65 at one end. At the end of clamp member 9b is extension 66 having a tongue 67 resting in a slot in the clamp member and held there by pressure cylinder 18. Said extension projects 45 through said boss and is attached thereto by washer 68 and nut 69, the latter being threaded on stud 70 which forms the end of the extension. Bearing 71 separates extension 66 from boss 65. Sleeve 63 is positioned on rod 64 between collars 50 72 and 73, which may be in the form of nuts threaded on said rod. Between the ends of sleeve 63 and collars 72 and 73 are springs 74 and 75. It will be seen that oscillation of rocker arm 51 by pitman 53 moves connecting rod 56 backward and forward, causing lever 59 to reciprocate rod 64, which in turn reciprocates clamp 9 longitudinally on the feed table.

Lateral movement of the clamp toward the shearing blades 7 and 11 is limited by fixed stop 76 attached to housing 1 and so positioned that it will be struck by clamp 9 when the clamp is moved forward, while movement of the clamp away from the shearing blades is limited by adjustable stop 77. Stop 77 is slidably mounted in 60 T-slot 78 in the housing by key member 79 integrally attached to said stop, and is adjustable with respect to fixed stop 76 by means of hand wheel 80 and screw bolt 81, said screw bolt being threaded through key member 79 and its reduced end being held in bearing 82, positioned at the end of T-slot 78, by nut 83 threaded on the end of said bolt. The other end of screw bolt 81 is carried by support 84, which also carries hand-wheel 80, which operates any well- 70 75 75

known type of means (not shown) for rotating said screw bolt, which rotation causes stop 77 to move toward or away from the shearing blades of the machine. Micrometer gauge 85 may be 5 provided on support 84 for enabling accurate positioning of stop 77. Any clearances between stop 77 and screw-bolt 81 are always held in the same direction by means of counter-weight 86 anchored to said stop by a suitable chain or 10 cable 87, passing over wheel 88. The lower edge of T-slot 78 may be graduated, as shown in Fig. 8, so that by means of these graduations and the micrometer gauge, the distance between fixed 15 stop 76 and adjustable stop 77 can be accurately determined and set at exactly the length of the cut desired.

Suitable means for supplying motive power to the machine are provided, such as electric motor 89, pinions 90 and 91 and gears 92 and 93, with 20 clutch 94 adapted to engage cooperating clutch mechanism 95 on gear 93, so that the crank shaft and the members mounted thereon may be caused to rotate whenever the operator so desires. Clutch 94 may be moved in and out of 25 operative engagement with the cooperating clutch mechanism 95 by any well-known means.

In the operation of the machine, the distance between stops 76 and 77 is first adjusted by hand-wheel 80 so that the clamp can move no further 30 than the length of sheet to be sheared, and connecting rod 56 is adjusted on rocker arm 51 so that if the stops were not present the sheet would be moved slightly more than the desired sheet length plus the sum of any possible accumulation of running clearances. The arcuate form and position of rocker arm 51 are such as to permit connecting rod 56 to be adjusted to any position along the slot in the rocker arm when clamp 9 is against fixed stop 76, without 40 in any way affecting the position of the clamp. It will be readily seen that oscillation of rocker arm 51 by pitman 53 moves connecting rod 56 backward and forward, causing lever 59 to reciprocate rod 64, which in turn reciprocates 45 clamp 9 longitudinally on the feed table, between stops 76 and 77. The additional distance travelled by studs 61 and 62 after clamp 9 has come to rest against either stop 76 or stop 77 will only result in compression of spring 74 or 50 spring 75, depending on the direction of travel of the clamp. Since the above arrangement insures that the feed clamp will always move the sheet a distance exactly equal to the length of sheet to be cut, regardless of any accumulation 55 of running clearances which otherwise would result in under-travel or over-travel of the clamp, the length of the sheets cut by the shear will always be equal, and will not be subject to variations caused by such accumulations.

60 Disc 31, eccentric 55, eccentrically mounted sleeves 8 and hold-downs 14 are so co-ordinated, and arranged to operate in such relation to each other, that the operation of the machine is as follows: Feed clamp member 9a is lowered by 65 piston rod 26 so that the sheet material is gripped between members 9a and 9b, whereupon the clamp moves the sheet material forward until the clamp strikes the stop 76 and the spring 74 is compressed, whereupon the hold-downs 14 descend and press the sheet material tightly 70 against the shear table, after which pressure is admitted to cylinder 18 and piston rod 26 raises member 9a so that the feed clamp releases the sheet and starts its backward movement, at 75 which time knife 1 falls, shearing off the desired

length of sheet material. Clamp 9 continues its backward movement until it strikes stop 77, when 5 spring 75 is compressed to take up the over-travel. Clamp member 9a is then again lowered into clamping position, after which the hold-downs 14 are released, and the sheet is moved forward again. This cycle is repeated as long as desired. It will be noticed that the action of the feed clamp is so timed with that of the hold-downs that the sheet is held at all times by either the clamp or the hold-downs, or both. 10

Although in the above description and in the accompanying drawings, the invention has been presented as applied to an automatic shearing machine, it of course could be applied to other 15 types of sheet-handling machines as well.

I claim:

1. In a feeding mechanism for handling sheet material, the combination of a rigid stop fixedly attached to the housing of the machine, a rigid 20 stop movably attached to said housing, a feed clamp mounted for reciprocation between said stops, said clamp having a flat gripping surface, a rod attached to said clamp, a coupling slidably mounted between springs on said rod, a lever attached to said coupling and pivotally mounted in the housing of the machine, a connecting rod 25 having one end attached to said lever and the other end attached to a rocker arm pivotally mounted in the housing of the machine, a pitman 30 pivotally connected at one end to an extension on said rocker arm and at the other end to an eccentric mounted on the crank shaft of the machine, and means for maintaining the feed clamp in positive material clamping relationship 35 during its reciprocation between said stops, said means being actuated by the crank shaft in timed relationship with the rocker arm.

2. In a machine for handling sheet material, a fixed rigid stop and an adjustable rigid stop, 40 means presenting flat surfaces extending substantially across the machine adapted to engage and feed material a distance corresponding to the distance between the stops, said means being adapted for adjustment to vary the length 45 of feed when at the position limited by the fixed stop, and means associated in timed relationship with said material engaging and feeding means adapted to insure positive engagement of the material during a feeding operation. 50

3. In a material handling mechanism, a bed plate for supporting one member of a material clamping device, a pressure cylinder secured to said member and having its piston rod secured to a second member superposed the first-men- 55 tioned member, means for imparting reciprocal movement to said clamping device between a fixed stop and an adjustable stop, said clamping device presenting flat surfaces in contact with a width of material during reciprocal movement, 60 resilient means associated with said reciprocal movement imparting means adapted to compensate for over-travel of the reciprocal movement imparting means with respect to the movement of said clamping device between said stops, a stationary clamping means disposed adjacent said fixed stop, means associated with said cylinder and reciprocal movement imparting means adapted to admit and exhaust pressure from said cylinder to actuate the clamping device into and out of material clamping relationship, said last-mentioned associated means being adapted to insure positive clamping of the material during 65 movement of said clamping device from the adjustable to the fixed stop, and micrometer means 70

associated with said adjustable stop adapted to permit accurate setting thereof.

4. In a material handling mechanism, a movable clamping device adapted to engage and advance material, said movable clamping device comprising opposed material engaging members, a bed plate for supporting said movable clamping device, a pressure cylinder secured to one of said members and having its piston directly secured to the opposed member, said cylinder securing means cooperating with the bed plate and adapted to permit relative sliding movement between the bed plate and movable clamping

device, means for imparting reciprocating movement to the clamping device as a unit along the bed plate, stops for controlling the extent of reciprocating movement, a plurality of positive spaced stationary material clamping devices adjacent one of said stops, and means incorporated in said movable material clamping device adapted to extend between said spaced stationary clamping devices in the extreme position of said movable clamping device adjacent said stationary clamping devices. 5 10

MOSES E. BROOKS.
